(57) **CLAIM**

The ornamental design for a syringe for liquid dispensing
machine, as shown and described.

DESCRIPTION

FIG. 1 is a front view thereof, showing a syringe for liquid
dispensing machine of my new design;

FIG. 2 is a right side view thereof;

FIG. 3 is a top plan view thereof;

FIG. 4 is a bottom plan view thereof;

FIG. 5 is a perspective view thereof;

FIG. 6 is another perspective view thereof;

FIG. 7 is a front view thereof, showing another embodiment
of the syringe for liquid dispensing machine;

FIG. 8 is a right side view thereof;

FIG. 9 is a top plan view thereof;

FIG. 10 is a bottom plan view thereof;

FIG. 11 is a perspective view thereof; and,

FIG. 12 is another perspective view thereof.

In the drawings, the broken lines depict portions of the
syringe for liquid dispensing machine that form no part of
the claimed design.

This article is a syringe for connecting to a liquid dispensing
machine. It is also used for transporting and storing liquid
materials such as solder paste, UV resin, silver paste, epoxy
resin liquid, etc. It is sealed with a syringe head cap on the
upper part and a syringe tip cap on the lower part, as shown
in the reference figure.
